(57) **CLAIM**

The ornamental design for a condom package, as shown and described.

DESCRIPTION

FIG. 1 is a perspective view of a condom package showing my new design, the side opposite that shown in FIG. 1 being identical thereto;

FIG. 2 is a top plan view thereof, the side opposite that shown in FIG. 2 being identical thereto;

FIG. 3 is a side elevational view thereof from the right of FIG. 2, the side elevational view from the left of FIG. 2 being identical thereto; and,

FIG. 4 is an end elevational view from the bottom of FIG. 1, the end elevational view from the top of FIG. 1 being identical thereto.
